BRAKING MECHANISM

Application filed December 22, 1926. Serial No. 156,446.

Objects of the present invention are to provide for the convenient and gradual application of brakes under air or liquid pressure automatically followed by the gradual, automatic release of the brakes; to provide for 5 properly and gradually controlling the brake mechanism from a suitable lever hand or foot operated; to provide for the installation of 10 brake mechanism adapted to accomplish the objects stated in a simple, efficient and gradual, as well as inexpensive manner; to provide for the gradual application and gradual release of the brakes generally in slowing down and quickly in emergency; to provide 15 for the proper control of the air or pressure fluid compressor; to prevent the quick thrust of the air or liquid pressure mechanism from operating the brake lever and at the same time to provide for permitting quick 20 application and release of the brakes; and to operate by air or liquid pressure an inlet and an air or liquid pressure exhaust valve from the same rod.

Other and further objects of the present 25 invention reside in means for accomplishing the above objects and still further objects will appear from the following description.

The invention consists of the novel construction hereinafter described and finally 30 claimed.

The nature, characteristic features and scope of the invention will be more fully understood from the following description taken in connection with the accompanying 35 drawings forming part hereof, and in which:

Fig. 1, is a view in top elevation of braking mechanism embodying the invention.

Figure 2, is a side or plan view thereof.

Fig. 3, is an end view of Fig. 2.

Fig. 4, is a view in section taken upon line 40 4-4 of Fig. 2.

Fig. 5, is an enlarged view, principally in section, of the lower right hand side of Fig. 2.

Fig. 6, is a view taken upon the line 6-6 of Fig. 9.

Fig. 7, is a view in section taken upon the line 7-7 of Fig. 9.

Fig. 8, is a view in section taken upon the 50 line 8-8 of Fig. 9.

Fig. 9, is a view upon an enlarged scale of certain parts shown in Fig. 5.

Fig. 10, is a view similar to Fig. 9 but illustrating a different position of parts; and

Fig. 11, is a fragmentary view illustrating 55 a somewhat modified arrangement wherein the exhaust pressure may be utilized for a further purpose.

For the purpose of illustrating my invention I have shown in the accompanying drawings two forms thereof which are at present preferred by me, since the same have been found in practice to give satisfactory and reliable results, although it is to be understood that the various instrumentalities of which 60 my invention consists can be variously arranged and organized and that my invention is not limited to the precise arrangement and organization of the instrumentalities as herein shown and described.

In the drawings the reference letter A designates the horizontally arranged two-part operating rod having a lost motion chamber therebetween which in practice may be connected with a hand lever or foot pedal 75 (not shown) and which forms no part of the present invention. Arranged in parallelism therewith and operating at all times in unison with said rod A are a pair of superimposed, horizontal rods designated B and C 80 respectively. The three rods are connected by an angular member or bracket H in any suitable manner. Thus, we find that movement of the rod A to the right in Fig. 9 carries the rod B in the same direction against 85 the tension of coiled spring a upon rod B so that the latter spring presses against the flanged sleeve b which slides with the forward motion of rod B to cause compression of said spring against valve d upon seat e, 90 operatively connected with which sleeve b is at e². The forward movement of rods A and B, thus described, causes the lower arm of the bell crank lever to press valve d down 95 upon its seat e. This movement of parts prevents the escapement of air or pressure fluid from chamber h. This position is probably best seen in Fig. 10. During this movement of parts, rod C has also moved to the right 100

in unison with rods A and B, thus causing the shoe or tapered cam f , which is fixed to rod C to move from the position shown in Fig. 9 to that shown in Fig. 10, thus gradually or progressively opening the tapered admission valve g against its spring g' to admit air or liquid pressure to enter chamber h , just referred to. It is to be noted that this movement of valve is possible because of the upper, 10 cylindrical stem g^2 which is in the path of travel of the tapered part of the shoe or cam f . As the valve g opens, air or liquid pressure passes from chamber h through ports j into cylinder k thus forcing the head D of piston D' toward the left in Fig. 10. This movement of the piston D', in the direction of the arrow, and now referring particularly to Fig. 5, moves the lever l around its pivot point c' . The upper end of lever l is provided with a yoke n which engages between the flanges of sleeve o which is fast upon rod F and which in turn is arranged in the same plane with operating rod A, together with connection F' of which the head P is a part 20 and head A ^{3} which encloses chamber G constitutes the direct connection with the brakes (not shown) and may in fact be termed the brake-rod connection, since lever L is provided with a yoke n engaged between the 25 flanges o which are secured to rod F for operating means of a sliding sleeve in end of rod A with a head P, being independent of the operation of the fluid pressure, on piston D. It may be stated, at this point, that the 30 connection F' is caused to move to the right in Fig. 5, that is, in the same direction as operating rod A, but at a greater speed, it being understood that the rod A at one end is provided with the cylindrical chamber G, within 35 which the cylindrical head P of connection F' is free to reciprocate at proper periods of operation. The chamber G, which is closed at each end, is slideable longitudinally upon a member A ^{1} , and through a boss A ^{2} , as carried by a fixed part of the apparatus. The 40 end of shaft A which moves through boss A ^{2} carried chamber G.

The above description has dealt chiefly with gradual brake application and the same 50 having been accomplished, a description will now be given of the brake release operation subsequent thereto. In this release operation, rods A, B, and C move to the left in Fig. 10, so that the bell crank lever c is moved about 55 its pivot point c^2 to permit raising of valve d through pressure of air or liquid within chamber h , said pressure thus egressing through ports e . The rod C meanwhile moves to the left in Fig. 10 and permits the shoe or 60 tapered cam f to close valve g and thus shut off air or liquid from the supply tank through connection I. However, in the connection, it is to be observed that when air 65 or liquid pressure within chamber h overcomes the pressure of spring a , the exhaust

ports e will open regardless of the position of operating rod A.

Taking up now the air or pressure fluid supply it may be stated that the same may be supplied from any suitable source forming 70 no part of the present invention. However, it is convenient to store the same in a tank or reservoir designated J, see Figs. 1, 2, 3, 4, and the storage is maintained at a constant or nearly equal pressure as possible. Obviously, a relief valve and pressure gage are 75 essential. A connection L leads from tank J to inlet connection I of the operating unit, see Fig. 3.

The tank or reservoir J may be supported 80 in any suitable manner as for example upon the chassis rail M of a motor vehicle, by means of a bracket N. In turn, for illustrative purposes only, the operating unit may be supported by a bracket O from the same 85 chassis rail M, because as previously stated, this invention is not limited to a motor vehicle braking device, although very desirable and efficient for that purpose. The brake may be applied with a gradual application 90 and a gradual release; also may be applied with an emergency application and an instant release, this being done by the quickness of the foot of operator.

In Fig. 11, there is shown a modified form 95 in which the rod E and lever l are the same as shown in the foregoing figures, but when the spring E' is too weak to properly release, pressure may be conveyed through tube p from valve d . In other words, the exhaust from ports e is caused to pass through connection p to chamber Y', thus forcing rod E forward against lever l to cause the release 100 of the braking parts by rearward movement of rod F to permit the escape of air at port Z. The operation of chamber Y is caused by the 105 instant release of air by means of valve d and only releases the brakes from the unit back and has no effect or action upon the chamber or piston D.

What I claim is:

1. In a device of the character stated comprising brake applying mechanism, three parallel rods operatively connected together for movement in unison, the uppermost rod being arranged to operate the other two rods, a chamber for containing pressure, and normally open at the top and closed at its bottom by vertically arranged valves, a horizontally disposed horizontally arranged tapered shoe for opening one valve and a bell crank lever for closing the other valve, and means connecting the first mentioned rod with the other two rods for effecting said movements.

2. In a device of the character stated comprising brake applying mechanism, three parallel rods operatively connected together for movement in unison, the uppermost rod being arranged to operate the other two rods, a lost motion device arranged between said upper-

most rod and the brake applying mechanism, a chamber for containing pressure, and normally open at the top and closed at its bottom by vertically arranged valves, a horizontally disposed tapered shoe for opening one valve and a bell crank lever for closing the other valve, and means connecting the first mentioned rod with the other two rods for effecting said movements.
